Primary Examiner — John Windmuller(74) *Attorney, Agent, or Firm* — Clause Eight IPS; Michael Catania(57) **CLAIM**

The ornamental design for a multi-element antenna, as shown and described.

DESCRIPTION

FIG. 1 is a top plan view of a multi-element antenna, showing our new design;

FIG. 2 is a side elevation view thereof;

FIG. 3 is a side elevation view thereof;

FIG. 4 is a front elevation view thereof;

FIG. 5 is a rear elevation view thereof;

FIG. 6 is a bottom plan view thereof; and,

FIG. 7 is a top perspective view thereof.

The broken lines show unclaimed environment only and form no part of the claimed design.
